UNITED STATES PATENT OFFICE.

GROVER C. WHITEFORD, OF CLEVELAND, OHIO.

DOOR-LOCK STRIKER PLATE.

Application filed March 18, 1926. Serial No. 95,614.

The present invention relates to door lock striker plates, and has for its object to provide a device of this character which embodies novel features of construction, where-
 5 by the part which is engaged by the latch bolt is movably mounted so that it can move with the latch bolt when there is relative movement between the parts, thereby avoiding wear between the parts. The door lock
 10 striker plate of this invention is particularly well adapted for use upon automobiles or other vehicles where the doors are subjected to constant jarring and vibration when the vehicle is in use. Under such conditions it
 15 will be readily understood that where there is the slightest looseness in the door the constant movement of the latch bolt against the striker plate will cause the parts to wear very rapidly, thereby increasing the loose-
 20 ness and causing more noise and rattle.

With the present invention the foregoing objection is overcome by providing the door lock striker plate with a bearing plate which is mounted thereon in a novel manner so
 25 that it will engage the latch bolt of the door and move therewith if there is any relative movement between the door and door jamb, thereby preventing the rapid wear of the latch bolt and striker plate which would
 30 otherwise take place.

While one particular embodiment of the invention is shown and described in this application for illustrative purposes, it will be understood that many modifications and
 35 changes can be made in the details of construction without departing from the spirit of the invention.

For a full understanding of the invention reference is to be had to the following description and accompanying drawings in which,

Figure 1 is a rear view of a door lock striker plate which is constructed in accordance with the invention.

Figure 2 is a longitudinal sectional view through the same on the line 2—2 of Figure 1.

Figure 3 is a sectional view taken on the line 3—3 of Figure 2.

Figure 4 is a detail perspective view of the body portion of the striker plate.

Figure 5 is a detail perspective view of the retainer plate which is applied to the back of the striker plate, and

Figure 6 is a side elevation of the slid- 55
 ably mounted bearing, while

Figure 7 is a top plan view thereof. Corresponding and like parts are referred to in the following description and indicated on all of the views of the drawing by like 60
 reference characters.

Referring to the drawings, the numeral 1 designates the body portion of the striker plate which is provided with the usual wedge shaped entering surface 2 against which the 65 latch bolt 3 of the door engages when the door is being closed. The inner end of the latch plate is recessed at the back thereof to provide a chamber 4. The back of the chamber is closed by a retainer plate 5 which may be held removably in position by suitable fastening members such as the screws 6. If desired the back of the striker plate may be recessed to receive the retainer plate. The 70 inner end of the chamber 4 provides a shoulder which has a substantially spaced and parallel relation to the end of the striker plate. A hard metal facing plate 7 is shown as applied to this shoulder.

A bearing member 8 is slidably mounted 80 within this chamber. As shown on the drawing the bearing member has a channel shaped formation, the side flanges projecting within the chamber 4 and receiving anti-friction rollers 9 between the same. These 85 antifriction rollers 9 are interposed between the bearing plate and the shoulder at the inner end of the chamber and the bearing plate is adapted to ride freely back and forth upon the rollers. The inner edge of 90 the rear flange of the channel shaped bearing plate 8 is provided with an outwardly deflected lip 10 which is received within a corresponding slot 11 in the retainer plate 5. This lip thus serves to prevent displacement 95 of the bearing plate from the striker plate, although it slides freely in the slot 11 as the bearing plate rides back and forth on the rollers 9.

The outer face of the bearing plate projects somewhat beyond the rear end of the striker plate and is provided at its ends with extensions 8a which extend over the striker plate and cover any space between the ends of the channel shaped portion of the bearing plate and the ends of the chamber. When the door is completely closed the latch bolt 3 thereof is projected over the bearing 100 105

plate 8 and engages the same as shown by Figure 2. The latch bolt may engage the bearing plate with considerable force, although if there is any relative movement between the door and door jamb, the bearing plate will remain in engagement with the door lock and ride freely back and forth on the rollers 9. The movement of the bearing plate 8 on the anti-friction rollers 9 is not accompanied by any wear and prevents the door latch bolt from cutting into the striker plate as it would otherwise do. The bearing plate 8 may be so mounted that it will have a slight tilting movement and can accommodate itself to the face of the latch bolt 3. The outer surface of the striker plate is shown as provided with the usual safety catch 12 which prevents the door from opening and causing an accident in the event it should not be securely closed.

Having thus described my invention what I claim as new and desire to secure by Letters Patent is,

1. A door lock striker plate including a body portion, and a bearing member adapted to engage the latch bolt and freely movable on the body portion while so engaged in a direction substantially parallel to the adjacent edge of the door opening and at right angles to the direction of movement of the latch bolt when engaging the same.

2. A door lock striker plate including a body portion, a bearing member movably mounted thereon and arranged for engagement with the latch bolt of the door, and anti-friction rollers for the bearing member.

3. A door lock striker plate including a body portion having a pocket in the rear end thereof, a bearing member slidably mounted in the pocket and extending through the mouth thereof for engagement with the latch bolt of a door, and retaining means for holding the bearing member in position, the direction of movement of the bearing member being at right angles to the direction of movement of the latch bolt as it engages therewith.

4. A door lock striker plate including a body portion having a pocket in the rear end thereof, a channel shaped bearing member slidably mounted within the pocket and extending through the mouth thereof for engagement with the latch bolt of a door, and anti-friction rollers arranged between the flanges of the channel shaped bearing member.

5. A door lock striker plate including a body portion having a pocket in the rear end thereof, a bearing member slidably

mounted within the pocket and projecting through the mouth thereof for engagement with the latch bolt of a door, a lip projecting laterally from the base of the bearing member, and a retaining plate having a slotted portion receiving the lip for cooperation therewith to hold the bearing member in place.

6. A door lock striker plate including a body portion having a pocket in the end thereof, a channel shaped bearing member slidably mounted within the pocket and projecting through the mouth thereof for engagement with the latch bolt of a door, anti-friction rollers arranged between the flanges of the channel shaped bearing member, a lateral lip projecting from one of the flanges of the bearing member, and a retaining plate formed with a slot receiving the said lip to hold the bearing member in place.

7. A door lock striker plate including a body portion, a bearing member slidably mounted upon the end thereof and arranged for engagement with the latch bolt of the door, anti-friction rollers upon which the bearing plate is movable, a detachable retaining plate, and means cooperating with the detachable retaining plate to hold the bearing member in place.

8. A door lock striker plate including a body portion, a bearing member adapted to engage the latch bolt and movable freely on the body portion while so engaged in a direction substantially parallel to the adjacent edge of the door opening and at right angles to the direction of movement of the latch bolt when engaging the same, and antifriction devices between the bearing member and body portion.

9. A door lock striker plate including a body portion, and a bearing member adapted to engage the latch bolt, said bearing member being mounted on the body portion to slide freely back and forth in a direction parallel to the adjacent edge of the door opening.

10. A door lock striker plate including a body portion, a floating bearing member mounted thereon and adapted to engage the latch bolt, the said floating bearing member being movable freely over the body portion in a direction substantially parallel to the adjacent edge of the door opening while the latch bolt is in engagement therewith, and means supporting the bearing member to permit the floating movement.

In testimony whereof I affix my signature.

GROVER C. WHITEFORD.
